F. A. DUSTMAN,

HEATER,

APPLICATION FILED APR. 1, 1915.

1,172,684.

Patented Feb. 22, 1916.

UNITED STATES PATENT OFFICE.

FREDERICK A. DUSTMAN, OF HOLDENVILLE, OKLAHOMA.

HEATER.

1,172,684.

Specification of Letters Patent. Patented Feb. 22, 1916.

Application filed April 1, 1915. Serial No. 18,557.

To all whom it may concern:

Be it known that I, FREDERICK A. DUSTMAN, a citizen of the United States, residing at Holdenville, in the county of Hughes and 5 State of Oklahoma, have invented certain new and useful Improvements in Heaters, of which the following is a specification.

This invention contemplates an improved heater especially adapted for attachment to 10 an ordinary table lamp although the construction employed is equally applicable for use in connection with various types of burners, and has as its primary object to provide a device of this character which 15 may be readily applied to a conventional type of lamp without the necessity of structural change therein, and which will be exceedingly simple in construction, to thus 20 produce a highly desirable article of manufacture.

The invention has as a further object and of equal importance with the foregoing object to provide a construction having the elements thereof so formed and arranged as 25 to produce a maximum result with a given amount of heat from the lamp.

Other and incidental objects will appear as the description proceeds and in the drawings wherein I have illustrated the preferred embodiment of my invention and wherein similar reference characters designate corresponding parts throughout the several views.

Figure 1 is a vertical sectional view showing my improved heater applied to a lamp of conventional form, Fig. 2 is a fragmentary perspective view of the heater, Fig. 3 is a perspective view showing one of the connecting wires detached, the said wires 40 being arranged to join the hood of the heater with the base thereof and providing handles, Fig. 4 is an enlarged fragmentary sectional view particularly showing the disposition of the tongues formed from the 45 hood of the device, and Fig. 5 is a fragmentary elevation particularly showing the contour of the tongues.

In carrying out my invention, I employ a frusto-conical base or body portion 10 which 50 may be formed of sheet metal or other suitable material and which is of a circumference at its base to removably fit upon the brackets 11 of a conventional type of lamp shown at 12 in Fig. 1 of the drawings, the 55 lamp being provided with a suitable burner

detachably supporting a chimney 13, in the usual manner.

The base 10 is of a length to extend above the mouth of the chimney as shown in Fig. 1 of the drawings and the lower margin 60 thereof is corrugated circumferentially as shown at 14. Mounted upon the base or body portion 10 at the upper extremity thereof is a frusto-conical hood 15 which, as in the instance of the body portion, is 65 also preferably formed of sheet metal although as will be clear, any other suitable material may be employed.

The wall of the hood 15 adjacent the lower margin thereof, is corrugated circumferentially as shown at 16 and a plurality of circumferential corrugations 17 are formed in said hood adjacent the upper extremity thereof, while the upper margin of the said hood is provided with a series of 75 circumferentially extending and vertically arranged corrugations 18.

Fitting over the upper small end of the hood 15 is an annular cap plate 19, the said plate being of a diameter considerably 80 greater than the diameter of the hood 15 at its smaller end and being provided, adjacent the periphery thereof, with a plurality of circumferentially extending corrugations 20. Struck from the body of the plate 19, 85 are a plurality of tongues 21, the free extremities of which are inserted within suitable slots formed in the wall of the hood 15 and then rebent, as best shown in Fig. 1 of the drawings for detachably connecting the 90 cap plate with the hood. It will be observed that the cap plate 19 forms a substantial closure for the hood at its upper end.

Struck from the wall of the hood 15 adjacent the lower extremity thereof, is a circumferentially spaced series of vertically arranged tongues 22, the said tongues being provided with serrated edges and being offset or bent longitudinally and inwardly adjacent their upper ends with the free extremities thereof projecting downwardly toward the larger end of the hood in spaced relation to the upper smaller extremity of the body portion 10. In thus striking the tongues 22 from the wall of the hood 15, a 105 circumferentially spaced series of vertically arranged openings 23 is provided in the hood adjacent its lower extremity, the walls defining said openings also being serrated and in this connection, attention is called to 110

the fact that the upper end or mouth of the body portion 10 is disposed in a plane passing through the said openings adjacent their upper extremities.

5 Connecting the hood 15 with the body portion 10, are truss wires 24 arranged at right angles to each other and inserted within suitable openings formed in the wall of the base 10 adjacent the upper extremity 10 thereof and in the wall of the hood 15 adjacent its lower extremity. As best shown in Fig. 1 of the drawings, these wires are arranged to cross each other at a point axially of the body portion of the hood, the hood being arranged concentric with relation to the body portion with the upper extremity of the body portion projecting a slight distance into the hood. As best shown in Fig. 1, the outer extremities of the wires 24 are 20 rebent to provide at points quadrantly spaced around the hood, radially extending handles 25, the ends of the wires being inserted within the upper extremities of the openings 23 and having the terminals 26 25 thereof again bent to engage against the inner face of the wall of the hood for securely connecting the handles thereto.

It will be observed upon references to Fig. 1 that the wires 24 adjacent the intersection thereof are adapted to rest upon the upper end of the chimney 13 to thus coact with the body portion 10 in supporting the heater upon the lamp. In use, heat rising from the burner through the chimney 13 30 will be discharged at the mouth of the chimney to enter within the hood 15. The heat being so discharged from the chimney will create a fresh air draft through the body portion 10 which draft, upon coming in contact with the heat issuing from the chimney, will tend to intensify the heated currents within the hood. These heated currents will 35 then rise within the hood to come in contact with the corrugations 17 and 18 and thus become thoroughly mingled.

As will be clear, currents rising within the hood 15 will be deflected by the cap plate 19 downwardly within the hood to strike the tongues 22 which, as will be seen, thus provide a series of radially extending baffle plates tending to further mingle the fresh air drafts with the heat rising from the chimney. The serrated edges of the tongues 22 as well as the serrated walls defining the openings 23 will, as the said currents flow over the tongues and through the openings, materially assist in thoroughly mixing the heated and fresh air currents issuing from the hood. The heated currents upon issuing through the openings 23 will immediately ascend to strike the outer corrugated margin of the cap plate 19 which action as will be understood, will tend to diffuse the heat within the room or other place where 65 the heater is used.

It will therefore be seen that I provide a very simple and efficient construction for the purpose set forth and while I have illustrated a heater especially adapted for attachment to an ordinary table lamp, still, it will be understood that by modifying the contour of the body portion 10 at its base, the said heater may be readily adapted for use in connection with various types of burners, this modification in construction being entirely within the spirit of the present invention as defined in the claims appended hereto.

As shown in Fig. 4 of the drawings, the free ends of the tongues 22 are bent inwardly toward the body portion 10 at a relatively sharp angle and may, if desired, be arranged to contact with the upper extremity of the said body portion at their outer terminals, to thus center the hood 15 upon the body portion. Preferably the tongues 22 are laterally enlarged adjacent the outer extremities thereof as more particularly shown in Fig. 5 of the drawings, so that the transverse width of each of the openings 23 formed in the hood is greater at the lower ends of the said openings, than at the upper ends thereof. Consequently, heat passing downwardly within the hood 15 as previously described and upon coming in contact with the tongues 22, will tend to create a suction within the upper restricted area of the said openings and consequently maintain a free circulation of heated currents through the body portion 10 and through the hood. The tongues 22 are preferably arranged to intersect the plane of the top of the body portion 10, or, in other words, are arranged to surround the open end of the said body portion so that the downwardly moving air currents within the hood will be delayed immediately at the point where the heated air currents issue from the body portion and will thus, while the heated air currents are at their maximum temperature, be intimately subjected to the influence thereof a relatively long time, to thus become the more intensely heated. The reason for arranging the openings 23 to intersect the open end of the plane of the body portion 10 will also now be clear since it will be seen that the said heated currents flowing downwardly within the hood 15, will be permitted to escape from the hood only after the said currents have 110 been heated to a maximum temperature.

Having thus described my invention, what I claim and desire to secure by Letters Patent is:—

1. A device of the character described including a hollow body portion, a hood connected to one extremity of the body portion, and a cap plate carried by the hood in spaced relation to the adjacent extremity of the body portion, the said hood being pro- 125 130 135

vided with an air current deflecting tongue intersecting the plane of the adjacent end of the body portion.

2. A device of the character described including a frusto-conical body portion, a frusto-conical hood fitting over one end of the body portion and arranged concentrically therewith, means connecting the hood with the body portion and providing handles projecting outwardly from the wall of the hood, and a cap plate carried by the hood.

3. A device of the character described including a hollow body portion, a frusto-conical hood fitting over one end of the body portion, the said hood being provided with a series of circumferentially spaced tongues extending between the hood and the body portion, means connecting the hood with the body portion, and a cap plate carried by the hood in spaced relation to the adjacent extremity of the body portion.

4. A device of the character described including a hollow body portion, a hood fitting over one end of the body portion, coacting truss members extending through the body portion and through the hood for connecting the hood with the body portion, the said members projecting radially of the hood to provide handles, and a cap plate carried by the hood.

5. A device of the character described including a hollow body portion adapted to be operatively supported by a lamp to surround the chimney thereof, a hood fitting over the upper end of the body portion and arranged in spaced relation thereto, truss members connecting the hood with the body portion and adapted to seat upon the upper extremity of the chimney, and a cap plate carried by the hood, the hood being provided with a plurality of circumferentially spaced openings disposed in a plane intersecting the adjacent upper end of the hood.

45 6. A device of the character described including a frusto-conical body portion, a frusto-conical hood fitting over the upper smaller end of the body portion and arranged in concentric relation thereto, coacting truss wires connecting the hood with the body portion, the said wires crossing each other at a point axially of the body portion and extending radially of the hood to provide handles, and a cap plate carried by the upper smaller end of the hood, the said hood having a series of circumferentially spaced tongues formed therefrom providing baffle plates between the upper end of the body portion and the lower end of the hood.

55 7. A device of the character described including a hollow body portion, a hood fitted over one end of the body portion, and means connecting the hood with the body portion and adapted to engage one end of a lamp

chimney disposed within the body portion for supporting the body portion upon said chimney.

8. A device of the character described including a hollow body portion, a hood fitted over one extremity of the body portion, and means carried by the body portion and adapted to engage one end of a lamp chimney disposed within the body portion for supporting the body portion thereon, the said means being engaged with the hood for supporting the hood upon the body portion.

9. A device of the character described including a hollow body portion, a hood fitted over one extremity of the body portion, and means connecting the hood with the body portion, said means intersecting at a point axially of the body portion and being adapted to engage one end of a lamp chimney disposed within the body portion for supporting the body portion thereon.

10. A device of the character described including a hollow body portion, a hood fitted over one extremity of the body portion, and angularly disposed coacting elements connecting the hood with the body portion and providing handles extending radially of the hood.

11. A device of the character described including a hollow body portion, a hood fitted over one extremity of the body portion, and means connecting the hood with the body portion, the hood being provided with a discharge opening wider at one end than at the other and intersecting the plane of the upper end of the body portion.

12. A device of the character described including a hollow body portion, a hood fitted over the upper end of the body portion, and means connecting the hood with the body portion, the hood being provided with a discharge opening intersecting the plane of the upper end of the body portion adjacent its upper end and being wider adjacent the lower end thereof than at its upper end.

13. A device of the character described including a hollow body portion, a hood fitted over one end of the body portion, and means connecting the hood with the body portion, the hood being provided with a discharge opening defined by walls having a plurality of tongues formed thereon extending into the said opening.

14. A device of the character described including a hollow body portion, a hood fitting over one extremity of the body portion, means connecting the hood with the body portion, and an air current deflecting tongue projecting between the hood and the body portion.

15. A device of the character described including a hollow body portion, a hood fitting over one extremity of the body portion, means connecting the hood with the

- body portion, and an air current deflecting tongue projecting between the hood and the body portion and provided with serrated edges.
- 5 16. A device of the character described including a hollow body portion, a hood fitted over one extremity of the body portion, means connecting the hood with the body portion, and an air current deflecting tongue carried by the hood and curving inwardly toward the body portion.
- 10 17. A device of the character described

including a body portion, a hood fitted over one extremity of the body portion and provided with discharge openings, and means 15 connecting the hood with the body portion and terminally engaged in said openings.

In testimony whereof I affix my signature in presence of two witnesses.
